UNITED STATES PATENT OFFICE.

FRANK G. HIGGINS AND ROBERT L. MILLER, OF SPOKANE, WASHINGTON.

AUTOMATIC-CONTROLLED RAILWAY STOPPING SYSTEM.

1,363,595.

Specification of Letters Patent. Patented Dec. 28, 1920.

Application filed May 31, 1919. Serial No. 300,982.

To all whom it may concern:

Be it known that we, FRANK G. HIGGINS and ROBERT L. MILLER, joint inventors, and citizens of the United States of America, residing at Spokane, in the county of Spokane and State of Washington, have invented new and useful Improvements in Automatic-Controlled Railway Stopping Systems, of which the following is a specification.

This invention pertains to the positive control of railroad trains and the like for the purpose of getting certain positive, automatic, mechanical effects regardless of the neglect or disobedience of other manually operative systems. The invention is particularly adapted to be used in connection with block systems.

The object of this invention, generally stated, is to provide an improved train stop mechanism which will positively control the movement of railroad trains within certain block limits. More specifically, this invention has for its object to provide for the positive locking of the "track" tripper in safety position until such a time as it shall be necessary for the tripper to come to danger position, for positively setting the trip at danger, and for positively resetting the trip to safety after it has been actuated. The operations are effected by the new and distinct construction hereinafter particularly described and illustrated in the accompanying drawings in which,

Figure 1, is a view in side elevation of our improved device, together with broken-away views of a locomotive, railway and railway block system, a portion thereof being diagrammatically shown, and showing the mechanism in a "train stop" position.

Fig. 2, is an enlarged vertical sectional view taken on the line 2—2 of Fig. 1.

Fig. 3, is a like sectional view, modified by showing the mechanism in a "train pass" position.

Fig. 4, is a sectional view taken on the line 4—4 of Fig. 2.

Fig. 5, is an enlarged sectional view taken on the line 5—5 of Fig. 3.

Fig. 6, is an enlarged sectional view taken on the line 6—6 of Fig. 5.

Fig. 7, is a sectional view taken on the line 7—7 of Fig. 4.

Fig. 8, is a sectional view taken on the line 8—8 of Fig. 3.

Fig. 9, is a broken-away view taken from the top of Figs. 2 or 3, and,

Fig. 10, is an enlarged sectional view on line 10—10 of Fig. 2.

In a detail description in which like numbers refer to like parts throughout the several views, we have shown a contact shoe 11 attached to a vertically slideable finger 12 attached to a valve 13, the finger 12 being slidably mounted in bearings 14, 15 and 16, the two former bearings being supported by a bracket 17 and the latter by the engine frame 18. The usual air-brake train line 19 is connected with the valve 13 and also with the engineer's brake operating valve 20. Inasmuch as this invention pertains exclusively to the mechanism connected with a train block system, that is tied into the road bed track and semaphore operating mechanism, no part of which is connected with the engine or train, it is thought that it will not be necessary to greatly enlarge upon the description of the engine or train mechanism, other than to occasionally refer to the parts and their operation. A normal block signal circuit comprises a battery 21, wire 22, semaphore mechanism 23, wire 24, switch 25 and wire 26. Two additional circuits are required to operate this mechanism. The first additional circuit comprises the above named elements together with the wires 27 and 28, Fig. 3, the magnet 29 and the wire 30. The second additional circuit comprises the first named elements together with the wires 27 and 31, the switch 32, the wire 33, the motor 34 and the wire 35, Fig. 3.

A ramp rail 36 mounted substantially parallel with and adjacent the railway track 37 is supported by levers 38 fulcrumed on a shaft 39 secured within a casing 40 at 41. The levers 38 extend downwardly within the casing 40 a substantial distance below the shaft 39 and have downwardly and outwardly extending arms 42 reinforced by braces 43. Secured to the outer ends of the arms 42 is a weight 44, the same being sufficient to normally hold the lever in a substantially vertical position, which maintains the ramp rail 36 in a position in relation to the railway shown in Fig. 2. Stops

45 serve as a barrier to the further rotation of the arms 38 in that direction. The levers 38 are arched at 46 as is also the wall 47 of the casing 40 adjacent thereto. An opening 5 48 is provided in the wall 47 to permit the necessary rotation of the levers 38 to effect the changes in position of the ramp rail 36. Arched roofs 49 are attached to the levers 38 and serve as coverings for the openings 10 48 to keep out snow, ice, water or other substances. A motor 34 is supported by a bracket 50 attached to the frame 40. Mounted in the casing 40 and journaled in the uprights 51 is a horizontal shaft 52 upon which 15 are mounted a pinion 53, a drum 54 and a gear 55, Fig. 4. Upon the side of the gear 55 is a ratchet gear 56. A shaft 57 extends from the motor 34 and carries at its outer end a pinion 58 which meshes with the gear 20 55, Fig. 4. Suspended within the casing 40 by means of brackets 59 is a cylinder 60 open at the end 61 and closed at the end 62. Small ports 63 are provided in the end 62. Within the cylinder 61 is mounted a piston 25 64 having an arm 65 carrying at its outer end a rack 66, which engages the pinion 53. Secured to the drum 54 is one end of a cable 67 which passes over the pulleys 68, 69 and 70 and has its other end secured to rod 30 38' connecting the lower ends of the levers 38. Secured to the shaft 52 is a key 71 which has a rotatable contact with the switch 32. The lower or free end of the switch 32 is circumscribed in its movement 35 by a keeper 72. Mounted on the support 51 against the gear 56 is a box 73 within which is secured a metal lever 74 fulcrumed at 75 on a support 76, Fig. 5. Within the box 73 is also mounted the magnet 29, the same being adjacent the end 74^a of the lever 74. 40 The lever 74 is curved outwardly at 77 so as to throw the line of gravity in that direction from the fulcrum 75. At the point 77 is secured an outwardly extending arm 78 45 which carries at its outer end a weight 79. The arm 78 extends through a slotted opening 80 in the wall of the box 73 and the weight 79 is on the outside of the box.

At the lower end of the lever 74, see Figs. 50 5 and 6, is a slot 81 through which passes a pin 82 pivotally connecting an arm 83 passing through an opening in the wall of the box 73 at 93 and having at its outer end a cylinder 84 within which is mounted a coil 55 spring 85. A pawl comprising a pin 86 supported by a head 87 extends outwardly through an opening 88 in the end of the cylinder, which pawl engages the ratchet gear 56. A stem 89 extending inwardly from the 60 wall of the box 73 is encircled by a coil spring 90 which bears against the lever 74 at 91. The lever 74 is adapted to rock from the fulcrum 75, the movement being limited by a stop 92 and by the magnet 29.

65 In the practical application of the device,

when the normal block circuit system is working in regular order and no train is in the block, the parts will be held in "safety" position, or in the position shown in Fig. 3, by means of the first additional circuit above 70 described whereby the magnet 29 holds the end 74^a of the lever 74 in the position shown in Fig. 5, the pawl 86 being held in engagement with the gear 56 thereby holding the pinion 58 and drum 54 against rotation and 75 the cable 67 serving to hold the lever 38 in the position shown in Fig. 3 as against gravity or the weight 44.

When a train enters the block in the normal train block system and the switch 25 is 80 opened by means of such system, gravity or the weight 44 operates to rotate the parts to the position shown in Fig. 2, bringing the ramp rail 36 to "danger" and which operates the air on the train line to stop the train. 85 In case the circuit on the regular train block system is for any reason broken, the parts will operate as above, thereby providing for a stopping of the train in case of disorder in the operation and causing the mechanism 90 to serve as an informer of disorder. When the parts have changed position from that shown in Fig. 3 to that shown in Fig. 2, the key 71 has rotated to come in contact with and to close the switch 32 thereby forming 95 the second additional circuit above described so that when the block is clear and the switch 25 closed, the motor 34 will operate to rotate the gear 55, drum 54 and shaft 52 and wind the cable 67 to again draw the 100 lever 38 to the position shown in Fig. 3 and bringing the ramp rail 36 to safety position. While this is taking place, the key 71 is being rotated in an opposite position and strikes the switch 32 and breaks the said second additional circuit. In the setting of the ramp rail to safety, the pinion 53 on the shaft 52 in its engagement with the rack 66 serves to draw the piston 64 in the cylinder 61 outwardly so that when the weight 44 105 operates to change the position of the lever 38 and the ramp rail 36, the rotation of the shaft 52 and engaging gear and drum will be cushioned in their rotation by the return stroke of the piston in the cylinder. When 115 the "first additional circuit" above described is broken, the coil spring 89 supplemented by the weight 79 serves to change the position of the lever 74 to disengage the pawl 86 from the gear 56. The weight 79 is made 120 sufficient in itself to serve this purpose, if by breakage or otherwise, the spring 89 fails. The coil spring 85 in the end 84 of the arm 83 serves to "ratchet" the engagement of the pawl 86 with the gear 56 in the rotation of 125 the gear 56.

What is claimed is:—

1. In an automatic controlled railway stopping system, a construction for co-operating with a tripping finger used in con- 130

- nection with an air-brake system on a train to set the brakes and stop the train, and an electrically controlled train block system, comprising a ramp rail mounted adjacent and substantially paralleling the railway track and adapted for sidewise movement to throw the same in or out of contact with the finger on the train, a casing in which is substantially mounted a shaft upon which are 5 levers supporting said ramp rail at their tops, said levers having laterally extending arms beneath the fulcrum, a weight on said arms, means between said levers and said electrically controlled track block system whereby 70 said ramp rail is held to safety position as against said weight, by means of a closed circuit on said electrically controlled track block system, such means comprising a cable attached to said levers, a rotatable shaft 75 upon which is mounted a gearing and a drum, the cable engaging said drum, a magnet mounted in circuit with said track block system serving to hold a pawl in said gearing to hold the same as against rotation, and 80 means for the automatic release of said pawl from such engagement when said circuit is broken and permit said weight to swing said levers to put the ramp rail in danger position, together with automatic means for 85 rotating the levers carrying the ramp rail, to place the ramp rail in safety position after the circuit on the track block system has been closed.
2. In an automatic controlled railway stopping system, a construction for coöperating with a tripping finger used in connection with an air-brake system on a train to set the brakes and stop the train, and an 20 electrically controlled track block system comprising a ramp rail mounted adjacent and substantially paralleling the railway track and adapted for sidewise movement to throw the same in or out of contact with the finger on the train, a casing in which is 30 substantially mounted a shaft upon which are rotatably fulcrumed, substantially vertical levers supporting said ramp rail at their tops, said levers having laterally extending arms beneath the fulcrum, a weight on said 35 arms, means between said levers and said electrically controlled track block system whereby said ramp rail is held to safety position as against said weight, by means of a 40 closed circuit on said electrically controlled track block system, such means comprising a cable attached to said levers, a rotatable shaft upon which is mounted a gearing and a drum, the cable engaging said drum, a 45 magnet mounted in circuit with said track block system serving to hold a pawl in said 50 gearing to hold the same as against rotation, and means for the automatic release of said pawl from such engagement when said circuit is 55 broken and permit said weight to swing said lever to put the ramp rail in danger position.
3. In an automatic controlled railway stopping system, a construction for coöperating with a tripping finger used in connection with an air-brake system on a train to set the brakes and stop the train, and an electrically controlled track block system comprising a ramp rail mounted adjacent and substantially paralleling the railway track and adapted for sidewise movement to throw the same in or out of contact with the finger on the train, a casing in which is substantially mounted a shaft upon which are 60 rotatably fulcrumed substantially vertical 65 levers supporting said ramp rail at their tops, said levers having laterally extending arms beneath the fulcrum, a weight on said arms, means between said levers and said electrically controlled track block system whereby 70 said ramp rail is held to safety position as against said weight, by means of a closed circuit on said electrically controlled track block system, such means comprising a cable attached to said levers, a rotatable shaft 75 upon which is mounted a gearing and a drum, the cable engaging said drum, a magnet mounted in circuit with said track block system serving to hold a pawl in said gearing to hold the same as against rotation, and 80 means for the automatic release of said pawl from such engagement when said circuit is broken and permit said weight to swing said levers to put the ramp rail in danger position, together with automatic means for 85 rotating the levers carrying the ramp rail, to place the ramp rail in safety position after the circuit on the track block system has been closed.
4. In an automatic controlled railway stopping system, a construction for coöperating with a tripping finger used in connection with an air-brake system on a train to set the brakes and stop the train, and an electrically controlled track block system comprising a ramp rail mounted adjacent and substantially paralleling the railway track and adapted for sidewise movement to throw the same in or out of contact with the finger on the train, a casing in which is substantially mounted a shaft upon which are rotatably fulcrumed substantially vertical levers supporting said ramp rail at their tops, said levers having laterally extending arms beneath the fulcrum, a weight on said arms, means between said levers and said electrically controlled track block system whereby said ramp rail is held to safety position as against said weight, by means of a closed circuit on said electrically controlled track block system, such means comprising a cable attached to said levers, a rotatable shaft upon which is mounted a gearing and a drum, the cable engaging said drum, a magnet mounted in circuit with said track block system serving to hold a pawl in said gearing to hold the same as against rotation and means for the automatic release of said pawl from such engagement when said circuit is broken and permit said weight to swing said levers to put the ramp rail in danger position, together with automatic means for rotating the levers carrying the ramp rail to place the ramp rail in safety position after the circuit on the track block system has been closed, such means comprising a motor connected with said gearing and tied into the electrically controlled track block system whereby the 100 gearing and said drum are rotated to swing 105 said drum, a magnet mounted in circuit with said track block system serving to hold a pawl in said gearing to hold the same as against rotation and means for the automatic release of said pawl from such engagement when said circuit is broken and permit said weight to swing said levers to put the ramp rail in danger position, together with automatic means for rotating the levers carrying the ramp rail to place the ramp rail in safety position after the circuit on the track block system has been closed, such means comprising a motor connected with said gearing and tied into the electrically controlled track block system whereby the 110 gearing and said drum are rotated to swing 115 said drum, a magnet mounted in circuit with said track block system serving to hold a pawl in said gearing to hold the same as against rotation and means for the automatic release of said pawl from such engagement when said circuit is broken and permit said weight to swing said levers to put the ramp rail in danger position, together with automatic means for rotating the levers carrying the ramp rail to place the ramp rail in safety position after the circuit on the track block system has been closed, such means comprising a motor connected with said gearing and tied into the electrically controlled track block system whereby the 120 gearing and said drum are rotated to swing 125 said drum, a magnet mounted in circuit with said track block system serving to hold a pawl in said gearing to hold the same as against rotation and means for the automatic release of said pawl from such engagement when said circuit is broken and permit said weight to swing said levers to put the ramp rail in danger position, together with automatic means for rotating the levers carrying the ramp rail to place the ramp rail in safety position after the circuit on the track block system has been closed, such means comprising a motor connected with said gearing and tied into the electrically controlled track block system whereby the 130 gearing and said drum are rotated to swing

the levers carrying the ramp rail to the opposite position and means for breaking the electrical connection with said electrically controlled train block system after the 5 levers have reached said opposite position.

5. In an automatic controlled railway stopping system, a construction for co-operating with a tripping finger used in connection with an air-brake system on a train 10 to set the brakes and stop the train, and an electrically controlled track block system comprising a ramp rail mounted adjacent and substantially paralleling the railway track and adapted for sidewise movement to 15 throw the same in or out of contact with the finger on the train, a casing in which is substantially mounted a shaft upon which are rotatably fulcrumed substantially vertical levers supporting said ramp rail at 20 their tops, said levers having laterally extending arms beneath the fulcrum, a weight on said arms, means between said levers and said electrically controlled track block system whereby said ramp rail is held to safety 25 position as against said weight, by means of a closed circuit on said electrically controlled track block system, such means comprising a cable attached to said levers, a rotatable shaft upon which is mounted a 30 gearing and a drum, the cable engaging said drum, a magnet mounted in circuit with said track block system serving to hold a pawl in said gearing to hold the same as 35 against rotation, and means for the automatic release of said pawl from such engagement when said circuit is broken and permit said weight to swing said lever to 40 put the ramp rail in danger position, and means for cushioning the rotation of the shaft gearing and drum in their rotation caused by their connection with said weight.

6. In an automatic controlled railway stopping system, a construction for co-operating with a tripping finger used in connection with an air-brake system on a train 45 to set the brakes and stop the train, and an electrically controlled track block system comprising a ramp rail mounted adjacent

and substantially paralleling the railway track and adapted for sidewise movement 50 to throw the same in or out of contact with the finger on the train, a casing in which is substantially mounted a shaft upon which are rotatably fulcrumed substantially vertical levers supporting said ramp rail at 55 their tops, said levers having laterally extending arms beneath the fulcrum, a weight on said arms, means between said levers and said electrically controlled track block system whereby said ramp rail is held to safety 60 position as against said weight, by means of a closed circuit on said electrically controlled track block system, such means comprising a cable attached to said levers, a rotatable shaft upon which is mounted a 65 gearing and a drum, the cable engaging said drum, a magnet mounted in circuit with said track block system serving to hold a pawl in said gearing to hold the same as 70 against rotation, and means for the automatic release of said pawl from such engagement when said circuit is broken and permit said weight to swing said lever to 75 put the ramp rail in danger position, and means for cushioning the rotation of the shaft gearing and drum in their rotation caused by their connection with said weight, such means comprising a rack connected with the gearing on said shaft, a cylinder 80 open at one end and closed at the other, 85 ports in the closed end of the cylinder, a piston mounted in said cylinder extending through the open end thereof, and a connection between said piston and rack whereby in the rotation of the shaft, gearing and 90 drum, the piston bears against the air in said cylinder and gradually forces the same through said ports.

In testimony whereof we affix our signatures in presence of two witnesses.

FRANK G. HIGGINS.
ROBERT L. MILLER.
